sets

Application February 17, 1938, Serial No. 190,997

3 Claims. (Cl. 122—240)

This invention relates to furnaces, and more particularly to an improved construction of furnace in which fuels may be burned either in suspension or in solid form on a grate.

Many manufacturing concerns utilize a fuel such as pulverized coal for a considerable part of their steam generating requirements and supplement this fuel with waste material, as for example wood refuse, resulting from manufacturing operations. Pulverized coal is burned in suspension, whereas wood refuse is usually burned on a grate. Because of the great differences in these fuels and in the type of combustion chamber best suited to them, it is a common practice to utilize separate furnaces, but this is expensive, inefficient and wasteful of space.

It is accordingly one object of the present invention to overcome these difficulties and to provide a comparatively simple and inexpensive steam generating furnace in which two widely differing fuels may be burned simultaneously or independently.

It is a further object of the invention to provide a furnace which will occupy comparatively little floor space, and which is adapted for the efficient combustion of one fuel in suspension and of a different fuel on a grate.

It is a further object of this invention to provide a furnace adapted for the efficient combustion of pulverized fuel in suspension and of a different fuel in solid form on a grate, the various parts being so constructed and arranged as to ensure automatic discharge of the incombustible residues from both fuels.

With these and other objects in view, as will be apparent to those skilled in the art, the invention resides in the combination of parts set forth in the specification and covered by the claims appended hereto.

In accordance with our invention in its preferred form, we provide a combustion chamber in which a fuel such as pulverized coal may be burned in suspension, this chamber having two opposite bottom walls which slope downwardly and inwardly toward a narrow central throat or opening extending transversely of the combustion chamber. Beneath this opening there is provided a longitudinally movable grate, which is preferably of the endless type. A solid fuel, such as wood refuse, is supplied to the front of the grate, and the ashes from both fuels are carried rearwardly by the grate and deposited in a suitable ash pit or sluice. Arches of refractory material extend forwardly and rearwardly from the central opening to ensure the ignition and effi-

cient combustion of the solid fuel. These arches are preferably supported by means of water tubes which continue upwardly to form cooling means for the sloping bottom walls of the upper combustion chamber and thus facilitate the discharge by gravity of the pulverized fuel ash.

Referring to the drawing illustrating one embodiment of the invention, and in which like reference numerals indicate like parts,

Fig. 1 is a longitudinal sectional view through a steam generating furnace;

Fig. 2 is an enlarged fragmentary section taken on the line 2—2 of Fig. 1; and

Fig. 3 is an enlarged fragmentary section taken on the line 3—3 of Fig. 1.

The embodiment illustrated comprises a steam boiler having a transverse lower drum 10 at the front and a transverse upper drum 11 at the rear, these drums being connected by a bank of upwardly and rearwardly inclined water tubes 12. Beneath the water tubes 12 there is provided a combustion chamber 14 having a front wall 15 and a rear wall 16. The front wall 15 is formed with an opening 13 through which a stream of pulverized fuel and combustion air may enter the chamber 14 from a burner 19 of any suitable type. Pulverized fuel is supplied to the burner from a suitable pulverizer 20 through a pipe 21. The combustion chamber 14 is provided with front and rear bottom walls 23 and 24 respectively which slope downwardly and inwardly toward a narrow central ash discharge throat or opening 25 extending transversely of the combustion chamber.

Beneath the ash discharge opening 25 there is provided a longitudinally movable endless grate 27 of any suitable construction, having a fuel hopper 28 at the front thereof to receive wood refuse or other fuel by gravity from a feeder 29 through a chute 30. The upper run of the grate 27 is arranged to travel rearwardly toward a rear wall 32 which is spaced slightly from the rear end of the grate to provide room for the downward discharge of ashes.

In order to protect the grate 27 from the radiant heat of the combustion chamber 14 and at the same time facilitate the ignition and combustion of the fuel on the grate, we provide a substantially horizontal front arch 34 spaced above the grate and extending forwardly from the transverse opening 25, and a substantially horizontal rear arch 35 spaced above the grate and extending rearwardly from the opening 25.

These arches are formed of refractory material capable of withstanding comparatively high

temperatures in service, and in the preferred construction they are composed of separate refractory blocks, as shown in Fig. 3, these blocks being grooved on their sides to fit spaced parallel water tubes which support the blocks. The front arch 34 is supported by water tubes 36 which extend rearwardly from a transverse horizontal header 37 at the front of the arch, and the rear arch 35 is supported by water tubes 39 which extend forwardly from a transverse horizontal header 40 at the rear of the arch. The headers 37 and 40 are supplied with water from the boiler drum 10 by means of one or more downcomer pipes 41 having branches 42 leading to the headers.

At the opening 25 the water tubes 36 and 39 are bent upwardly and extend along the corresponding bottom walls 23 and 24 in cooling relation with these walls, the upwardly extending portions of the tubes preferably being exposed to the radiant heat in the combustion chamber 14. The tubes 36 connect at their upper ends with a transverse horizontal header 44 which in turn is connected to the boiler drum 10 by means of upright water tubes 45. These tubes 45 extend upwardly along the heat exposed face of the front wall 15, and certain of them may be bent laterally if necessary to clear the burner opening 18. The tubes 39 extend upwardly along the heat exposed face of the rear wall 16 and they may be connected directly with the boiler drum 11, but in the case of a very high combustion chamber it will probably be difficult to obtain tubes of sufficient length. In such event the upper ends of these tubes 36 will be connected to a transverse horizontal header 47 which is connected to the drum 11 by means of upright water wall tubes 48.

The water tubes 36 and 39 are arranged with their centers spaced apart a distance of approximately twice the outside diameter of the tubes. With some fuels and operating conditions this may provide sufficient cooling for the sloping bottom walls 23 and 24. However, in order to make it possible to operate satisfactorily at high combustion rates with fuels having low ash-fusion temperatures, we preferably provide additional water tubes to form substantially completely water cooled metallic surfaces to direct the falling ashes into the opening 25. For this purpose we have provided a series of water tubes 50 with their opposite ends connected to the headers 40 and 47 in a staggered arrangement relative to the tubes 39. Along the rear wall 16 and the rear bottom wall 24 the tubes 50 are located in the same plane as the tubes 39, but adjacent the arch 35 the tubes 50 are bent outwardly with respect to the tubes 39 so that there will be no interference with the mounting of the refractory blocks of the arch on the tubes 39. A similar construction is utilized at the front of the furnace, where we have provided a series of water tubes 52 with their opposite ends connected to the headers 37 and 44 in a staggered arrangement with respect to the tubes 36. These tubes 52 are located in the same plane as the tubes 36 along the front bottom wall 23, but adjacent the arch 34 they are bent outwardly from the tubes 36 to avoid interference with the support of the refractory blocks of the arch.

The operation of the invention will now be apparent from the above disclosure. Pulverized fuel is discharged through the opening 18 by means of the burner 19, and combustion takes place in the chamber 14. Solid fuel, such as wood refuse, is delivered to the hopper 28 by the chute 75

30 and is carried rearwardly by the grate 27, combustion taking place during this rearward movement. The refractory arches 34 and 35 are maintained at a high temperature by the heat of combustion, and the front arch 34 in particular radiates heat on the incoming green fuel, thus evaporating the moisture therefrom, distilling the volatile matter from the fuel and igniting the solid residue. Since combustion takes place progressively during the rearward travel of the fuel, the nature of the gases arising from the front portion of the fuel bed is radically different from that of the gases in the rear. Usually the gases at the front are somewhat deficient in air for combustion, whereas those at the rear may contain an excess of air. The arches 34 and 35 force all of these gases to enter the comparatively narrow throat 25, where a mixture takes place so that all the combustible gases may be consumed efficiently and without undue quantities of air in excess of what is theoretically required. The hot gaseous products of combustion pass upwardly through the chamber 14 and into contact with the heating surfaces of the steam boiler thereabove in a well known manner. The ashes from the pulverized fuel separate from the flame by gravity and fall to the sloping bottom walls 23 and 24. Because of the cool metal surfaces afforded by the water tubes the ashes will not adhere to these walls but will slide down them and drop through the throat 25 to the grate 27. The grate will therefore serve as a means for conveying the pulverized fuel ash rearwardly and discharging the same. Either fuel may be burned alone if desired. In case pulverized fuel is being burned alone, the grate 27 may be operated continuously, or it may be operated intermittently whenever an appreciable quantity of ashes has accumulated thereon. Steam will of course be generated in the various water tubes and discharged upwardly into the drums 10 and 11.

In the claims appended hereto we have for convenience used such expressions as "transversely," "longitudinally," "forwardly," "rearwardly," etc., in order to set forth the claimed structure more clearly. It is to be understood, however, that these expressions are not to be considered as limitations except in so far as they define the relative positions of the various elements included in the claims.

Having thus described our invention, what we claim as new and desire to secure by Letters Patent is:

1. A furnace comprising walls enclosing a combustion chamber of sufficient size for the burning of pulverized fuel in suspension, means to supply pulverized fuel to the chamber for combustion in suspension therein, the chamber having two opposite bottom walls which are fully exposed to the radiant heat of the burning fuel and slope downwardly and inwardly toward a narrow central opening extending transversely of the combustion chamber, a longitudinally movable grate located beneath the opening, means to supply wood refuse to the grate for combustion thereon, arches of refractory material extending forwardly and rearwardly from the central opening to ensure ignition of fuel on the grate and to direct the gases arising from the fuel bed into the opening to mix said gases, and water circulating means supporting said arches and extending upwardly therefrom in cooling relation with said sloping bottom walls.

2. A furnace comprising walls enclosing a combustion chamber, means to supply fuel to the

chamber for combustion in suspension therein, the chamber having two opposite bottom walls which slope downwardly and inwardly toward a narrow central opening extending transversely of the combustion chamber, a longitudinally movable grate located beneath the opening, means to supply fuel to the grate for combustion thereon, blocks of refractory material arranged to form arches which extend forwardly and rearwardly from the central opening to ensure ignition of the fuel on the grate and to direct the gases arising from the fuel bed into the opening to mix said gases, spaced water circulating tubes arranged to support the refractory blocks, the tubes having portions extending upwardly from the arches in cooling relation with said sloping bottom walls, and additional water circulating tubes located between the upwardly extending portions of the first mentioned tubes to provide additional water cooling for said sloping bottom walls.

3. A furnace comprising walls enclosing a combustion chamber, means to supply fuel to the chamber for combustion in suspension therein, the chamber having two opposite bottom walls which slope downwardly and inwardly toward a

5 narrow central opening extending transversely of the combustion chamber, a longitudinally movable grate located beneath the opening, means to supply fuel to the grate for combustion thereon, arches of refractory material extending forwardly and rearwardly from the central opening to ensure ignition of fuel on the grate and to direct the gases arising from the fuel bed into the opening to mix said gases, transverse headers adjacent the front portion of the front arch and the rear portion of the rear arch respectively, means to supply water to the headers, spaced water circulating tubes connected to the headers and arranged to support the arches, the tubes having portions extending upwardly from the arches in cooling relation with said sloping bottom walls, and additional water circulating tubes connected to the headers and extending above the arches and thence upwardly between the upwardly extending portions of the first mentioned tubes to provide additional water cooling for said sloping bottom walls.
